UNITED STATES PATENT OFFICE.

DRURY T. KIRKPATRICK, OF DALLAS, TEXAS, ASSIGNOR TO THE KIRKPATRICK VAPOR BURNER COMPANY, OF SAME PLACE.

VAPOR-BURNER.

SPECIFICATION forming part of Letters Patent No. 434,791, dated August 19, 1890.

Application filed January 16, 1890. Serial No. 337,084. (No model.)

To all whom it may concern:

Be it known that I, DRURY T. KIRKPATRICK, a citizen of the United States, residing at Dallas, in the county of Dallas and State of Texas, have invented certain new and useful Improvements in Vapor-Burners; and I do declare the following to be a full, clear, and exact description of the invention, such as will enable others skilled in the art to which it appertains to make and use the same.

My invention has relation to improvements in vapor-burners; and it has for its object to provide a device for cooking or heating, in which oil and water are united in a common vapor or gas and burned as a fuel.

The improvements will be fully understood from the following description and claims, when taken in connection with the accompanying drawings, in which—

Figure 1 is a vertical diametrical sectional view of my improved burner, showing the construction and position of the respective chambers; and Fig. 2 is a top plan view of the cap or cover.

Referring to the accompanying drawings by letter, A indicates my improved water and oil vapor burner. This burner A consists of three apartments or chambers, two for the reception of oil and water and the other for the reception of the gas or vapor generated therefrom.

B indicates the base chamber or apartment of the burner. This chamber B, which is designed for the reception of coal-oil or crude mineral oil, is provided with a concave bottom, it having been found that the same will facilitate the feed of the air to the draft-tube presently to be described. The chamber B, and likewise the other chambers, are preferably cylindrical in form, and the wall of the said chamber B is provided in its upper inner edge with a recessed female threaded portion for the reception of the succeeding upper chamber.

a indicates a threaded opening cut in the wall of the chamber B to receive a pipe, through which oil is fed to the said chamber.

C indicates the intermediate chamber or cylinder, which is designed for the reception

of the water. This chamber C, the bottom 50 of which is flat and has a recessed threaded portion to engage with the threaded portion of the wall or chamber B, is provided at its top with a recessed female screw-threaded portion, similar to that of the chamber B, for 55 the reception of the threaded portion of the top cylinder or chamber.

e indicates an annular opening, which is cut in the wall of the intermediate or water chamber C. This opening e, the wall of which is 60 threaded, is designed to receive a pipe or tube, through which the water is fed to said chamber.

D indicates the top chamber, in which the generated vapor or gas from the water and 65 oil is mingled. This chamber D is provided with a flat bottom portion, the outer edge of which is recessed and threaded to engage with the interior threads of the wall of chamber C, and it is also provided at the top of 70 the cylindrical wall with an interiorly-recessed threaded portion to engage the threads of the cap portion of the burner.

E indicates the cap or top portion of my burner, the periphery of which is provided 75 with circumferential threads to engage the threads of top cylinder or chamber D, in the recess of which it is seated. This cap portion is provided at diametrically-opposite points on its face about midway between its 80 center and circumference with lugs or projections b, which serve to facilitate the unscrewing of the cap when it is desired to remove the same.

At the center of the concave bottom of the 85 cylinder B, I provide an annular opening, the wall of which is threaded to receive a hollow threaded nut or seat F. This nut F is provided with an opening through its central portion, the lower portion of said opening 90 being larger than the top portion, which is reduced, as shown, to facilitate the draft or force of the air-induction.

The wall of the upper portion of the reduced opening is threaded, as shown, to receive the threaded end of the air-conducting tube G, which is preferably of the comparative diameter shown. This tube G, which ex-

tends, as shown, almost to the base of the cap-nut of the burner, is intended to conduct a draft of air from below the bottom of the device to the burner-cap, where it forms a suction or draft in the generating-chamber of cylinder D, whereby the vapor of the water and oil in the successive lower chambers is drawn up thereto, and by reason of the current of air mingled and combined in a vapor of a highly-combustible nature, whereby a bright clear light and heat of high degree is furnished when the burner is ignited.

The bottom wall of chamber C is provided with a central annular opening, the wall of which is threaded to receive a connecting tube or sleeve H, which is exteriorly threaded to engage with the threads of the opening of said bottom wall. This tube H, which conducts the vapor or gas from the bottom cylinder or oil-chamber, extends up through the bottom wall of the generating-chamber a slight distance, said bottom plate being provided with a central annular opening of a diameter slightly greater than that of the tube H, whereby a communication is effected between the water and generating chambers for the passage of the water-vapor. The cap-plate or top E is also provided with a central annular opening, the wall of which is threaded to receive a hollow nut F', which is provided with exterior threads to engage the threads of the wall of the annular opening. This nut F', which is seated in the annular opening of the cap-plate, is provided in the upper portion of the wall of the annular opening with interior threads to receive the lower portion or section I of the burner proper. This section I of the burner is shouldered, as illustrated, to form a shallow cylinder for the vapor when the burner is in operation. The depending body portion d of the burner-section I is provided with a central annular opening of two diameters, the lower portion being larger than the upper and provided at its top with a rounded wall adapted to promote the draft.

At diametrically-opposite points in the wall of the cylinder portion of the burner-section I form minute perforations for the emission of the flame when in operation, of which there may be any desired number. The wall of the burner-section is also provided at its top upon its exterior surface with a circumferential threaded portion to engage the threads of the cap portion of the burner.

J indicates the upper or cap section of the burner proper. This cap-section J is provided with a depending flanged wall, which is threaded on its inner side to engage the threads of the lower section and secure it thereto. The cap of the burner proper is also provided in its central portion with a small annular opening for the emission of flame when in operation.

K indicates a depending flanged portion,

which forms the base or stand of my improved oil-burner. This stand K, which is preferably of a thickness similar to that of the wall of chamber B, and which, if desired, may be formed integral therewith, is provided in its periphery with numerous openings of the comparative size illustrated.

L indicates a plug, which is threaded on its exterior surface to engage the lower threads of the wall of annular opening in bottom of cylinder B. This plug L, which is designed for use when the device is not in use, is intended to stop the draft or circulation of air up through the ventilating-tube and thus prevent the evaporation of the oil and water which is promoted by said draft.

In operation, when oil and water have been fed to their respective cylinders or chambers, the plug L is removed and the burner placed upon a stove or other heater to facilitate the primary evaporation of the oil and water. The forcible draft caused by concave bottom and reduced opening of the tube forms a suction and current of air in the generating-chamber, which promotes the evaporation of the water and oil, the vapor of which is thoroughly mixed by said current of air and fed to the burner. After a short time the oil in the bottom of the burner becomes heated and boils the water in the chamber above, and the burner proper is then ignited and the burner removed from the heating agent, the evaporation being now facilitated by the heat from the burning vapor.

Having described my invention, what I claim is—

1. In a vapor-burner, substantially as described, the combination, with the mixing-chamber having a top or cap and a burner connected therewith, of an oil-chamber and a water-chamber connected, respectively, with said mixing-chamber, and an air-induction tube leading from the bottom of the device to the mixing-chamber, substantially as specified.

2. In a vapor-burner, substantially as described, the combination, with the mixing-chamber having a burner connected therewith, of a water-chamber and an oil-chamber arranged beneath the said mixing-chamber, the threaded tube seated in the bottom wall of the water-chamber and extending up into the mixing-chamber, and the air-induction tube leading from beneath the oil-chamber up through the threaded connecting-tube to the mixing-chamber, substantially as described.

3. In an oil and water vapor burner, the combination of an oil-chamber, a water-chamber, and a mixing-chamber arranged, respectively, one above the other, the connecting-tube threaded at its lower end to engage the threads of the annular opening in bottom of water-chamber and forming a communication between the oil and mixing chambers,

the bottom of the mixing-chamber being provided with an annular opening to form a communication between the same and the water-chamber, the burner proper seated in the

5 cap-plate of the mixing-chamber, the air-induction tube leading from the center of the concave bottom of the oil-chamber up through the connecting-tube to the mixing-chamber, and the depending perforated flange for feed-

ing air to the induction-tube, all adapted to operate substantially as specified.

In testimony whereof I affix my signature in presence of two witnesses.

DRURY T. KIRKPATRICK.
